(57) CLAIM

The ornamental design for an ink storage attachment, as shown and described.

DESCRIPTION

FIG. 1 is a front, top, and right side perspective view of an ink storage attachment showing our new design;

FIG. 2 is a front, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof; and,

FIG. 8 is a right side view thereof.

The broken lines illustrate portions of the ink storage attachment and form no part of the claimed design.

1 Claim, 8 Drawing Sheets
